CLAIM

The ornamental design for a vehicle wheel front face, as shown and described.

DESCRIPTION

FIG. 1 is a front perspective view of the vehicle wheel front face showing my design;

FIG. 2 is a front elevation view of the vehicle wheel front face of FIG. 1;

FIG. 3 is a left side elevation view of the vehicle wheel front face of FIG. 1;

FIG. 4 is a right side elevation view of the vehicle wheel front face of FIG. 1;

FIG. 5 is rear elevation view of the vehicle wheel front face of FIG. 1;

FIG. 6 is a top plan view of the vehicle wheel front face of FIG. 1; and,

FIG. 7 is a bottom plan view of the vehicle wheel front face of FIG. 1.

In the drawings, the broken lines depict environmental subject matter and portions of the vehicle wheel front face that do not form any part of the claimed design.
